PERMANENT MAGNET LATCHING TYPE VACUUM RELAY

Victor E. De Lucia, Santa Monica, and Bruce C. Meland, Los Angeles, Calif.; said Meland assignor to Teer Laboratories, Inc., Los Angeles, Calif., a corporation of California

Filed June 8, 1965, Ser. No. 462,260
2 Claims. (Cl. 335—153)

The present invention relates to high voltage vacuum relays; and it relates more particularly to miniature, high-voltage vacuum relays which are actuated from one state to another by brief pulses, and which do not require a steady flow of current to be maintained in any particular state.

As is well known, for usual prior art relay operations, a relay coil is energized by a continuous current to establish the relay contacts in a particular state, and when the current is terminated, the relay contacts are returned, usually by spring action, to their original state.

Other types of prior art relays are provided with latching means, whereby, once the relay is energized, its contacts are maintained in the particular state to which they were actuated, even after the energizing current is terminated. However, this latter type of relay still requires that the applied current which actuates the relay be so applied for a sufficiently long interval to permit the relay contact to assume the particular state, before the relay can be latched.

The above mentioned requirement of a continuous flow in the usual type of prior art relay, and slow response in this type of relay and in the latching type of relay, has seriously limited the use of mechanical relays, especially in high speed electrical circuits.

The use of high voltage vacuum relays is widespread in many applications, including space vehicles, missiles and the like. However, the use of this type of relay, likewise, has been limited because of the slow response time, and also because of the requirement for a continuous current flow through the relay coil in order to maintain the relays in their energized condition.

The high voltage vacuum relay is advantageous in that its contacts are housed in an evacuated envelope and are not subject to degradation due to arcing, which would normally occur if the contacts were operated in the usual atmosphere.

As indicated above, the application of the high voltage relay, and its field of usefulness, would be vastly increased if it were not for the fact that, prior to the present invention, the relays for many purposes were not sufficiently fast in their response. Moreover, such relays required continuous current, rather than brief pulses, in order to energize their operating coils.

The concepts of the present invention, which provide a vacuum relay capable of responding to extremely brief pulses, enables the relay of the invention to be constructed with relatively high ampere-turns for increased sensitivity. Moreover, this is achieved without the problems encountered in the prior art relay of this particular type, in which current is drawn through the energizing coil for prolonged periods of time, when the relay is energized.

An object of the present invention, therefore, is to provide an improved high voltage vacuum relay which exhibits bistable characteristics and which may be pulsed by extremely brief pulses from one stable state to the other.

Another object of the invention is to provide such an improved relay which is capable of responding to such extremely brief pulses, since its latching operation does not depend upon actual armature movement to become effective. Rather, a brief pulse applied to the relay im-

2

mediately changes the state of the remanent magnetization of an element included in the relay, and that particular element subsequently acts either to attract or repel a permanent magnet armature, so as to establish the relay in one stable state or the other.

Another object of the invention is to provide such an improved high voltage vacuum relay which utilizes a pivoted armature, the armature having no associated springs or other resilient members, so that problems of mechanical resonances are obviated.

Yet another object of the present invention is to provide an improved high voltage vacuum relay which utilizes a low mass, low inertia armature and which does not exhibit any tendency to spurious operation, even in the presence of excessively high vibratory conditions.

The improved relay of the present invention may utilize, for example, a bistable magnetic element which may be composed, for example, of a magnetic alloy referred to as "Remendur." This is a vanadium, cobalt, and iron alloy recently developed by the Bell Telephone Laboratories. The magnetic alloy is described, for example, in the Bell Laboratory Record for March 1964.

Remendur is composed, for example, of 2.5% vanadium, 49% cobalt, and 48.5% iron. This magnetic alloy is capable of exceedingly high values of remanence, for example, up to 21,500 gauss. This magnetic alloy exhibits a unique combination of magnetic and mechanical properties, ideally suited for the purposes of the present invention. The alloy has, for example, an essentially square hysteresis loop for efficient switching operation. It also has a comparatively stable coercive force in the range of 20-60 oersteds. It has essentially isotropic magnetic properties, and a high Curie temperature.

Moreover, the magnetic alloy, Remendur, has sufficient malleability and ductility to permit it to be processed into thin strips. Moreover, Remendur can be easily electroplated in order to enhance its electrical conductivity. Finally, the alloy responds to simple heat treatment.

When an element is formed of a bistable magnetic material as Remendur, and when a coil magnetically coupled to the element is successively pulsed by electrical pulses of opposite polarity, the element is caused to assume corresponding first and second remanent magnetic conditions.

For example, when the aforesaid element is pulsed so as to change its magnetic remanent condition from one polarity to another, the change is instantaneous, as noted above, and the change may be produced by an exceedingly brief electric pulse. Thereafter, in its normal response time, the relay armature responds to the changed remanent condition of the element to be attracted or repelled thereby so as to change the state of the relay contacts. Then, the relay remains in its latter state, until an opposite polarity pulse changes the remanent condition of the element back to its original polarity.

A permanent magnet is employed in the embodiment of the invention to be described, so as to establish the armature with a selected magnetic polarity. The permanent magnet preferably is positioned outside the evacuated envelope, and it may be replaceable to provide different magnetic strengths, as desired.

Moreover, the external positioning of the permanent magnet enables the evacuated envelope to be subjected to usual high vacuum and high temperature outgassing procedures without the permanent magnet being in the assembly. This prevents degradation of the permanent magnet which would occur if it were mounted within the envelope during the outgassing operation.

The features of the invention which are believed to be new are set forth in the claims. The invention itself, however, together with further objects and advantages thereof, may best be understood by reference to the fol-

lowing description, when the description is taken in conjunction with the accompanying drawing, in which:

FIGURE 1 is a plan view of an improved vacuum relay constructed in accordance with the concepts of the invention; and

FIGURE 2 is a fragmentary side sectional view of the assembly, taken essentially along the line 2—2 of FIGURE 1.

The relay assembly, as shown in the drawing, includes an envelope 10. This envelope, in accordance with the usual vacuum relay procedure, is evacuated, so that the relay contacts operate in a vacuum, for reasons well understood to the art.

A first terminal pin 12 is sealed in one end of the envelope 10, the envelope having an essentially cylindrical configuration in the illustrated embodiment. This terminal pin 12 may be formed of any suitable electrically conductive material, such as tungsten.

A rod 14 is mounted on the inner end of the pin 12, and this rod is attached to an element 16. The element 16 may be composed of "Remendur," or equivalent material, so as to exhibit the aforesaid bistable remanent magnetic properties. The rod 14 is also electrically conductive, and it supports the element 16 rigidly within the envelope 10. An appropriate electrical contact 18 composed, for example, of tungsten, is affixed to the inner end of the element 16.

An electrical coil 20 is mounted on the envelope 10 in position to surround the element 16, and the coil is magnetically coupled to the element. The coil 20 responds to brief electrical pulses selectively to change the magnetic remanent condition of the element 16 from one magnetic polarity to the other.

A further terminal rod 22 is sealed to the opposite end of the envelope 10. This latter terminal rod may be composed, for example, of Kovar. A member 24 composed, for example, of soft iron, is welded, or otherwise affixed, to the inner end of the rod 22, the member 24 being positioned within the envelope 10.

An armature 26 is positioned in the envelope 10 to make selective contact with the element 16. The armature has a contact 28 composed, for example, of tungsten. The contact 28 on the armature 26 engages the contact 18 on the element 16, when the armature 26 is moved against the element 16.

The armature 26 is supported by means of a rod 30 on the end of the member 24, the rod 30 being pivoted to the member 24 by means of an appropriate pivotal coupling 32. The armature 26 and rod 30 may both be composed of an appropriate magnetizable material, such as soft iron.

In addition, a non-magnetic rod 34 is rigidly fastened to the inner end of the member 24, and the rod 34 extends along the length of the envelope 10 to the point at which the armature 26 overlaps the element 16.

A magnetic member 36 is mounted on the end of the rod 34, and this latter member may be composed of an appropriate magnetizable material, such as soft iron. As shown in the drawing, the member 36 overlies the end of the armature 26, so that armature engages the member 36 when it is displaced from the element 16.

A permanent magnet 40 is removably mounted in the terminal 22, as shown, and externally of the envelope 10, for the reasons explained above.

It will be appreciated that when an electric pulse of a first polarity is passed through the coil 20, the element 16 assumes a first magnetic remanent condition, so that it attracts, for example, the armature 26. The armature 26, of course, is established in a permanent magnetic state by the permanent magnet 40. The attraction of the element 16 is sufficient to cause the armature 26 to move away from the member 36.

Then, when a magnetic pulse of opposite polarity is

passed through the coil 20, the element 16 assumes the opposite magnetic remanent condition, so that it repels the armature 26, and causes it to move against the member 36.

5 The magnetic attraction between the armature 26 and the member 36 is sufficient, so that the member 36 holds the armature against any movement, even in the presence of excessively high vibratory conditions. In this manner, spurious closures of the contacts 28 and 16 are prevented.

10 Appropriate electrical connections can be made to the terminals 12 and 22; and a contact is established between these two terminals, whenever the relay is energized so as to draw the armature 26 down into engagement with the element 16.

15 The fact that the armature 26 is pivotally mounted in the envelope 10, without the use of springs, or the like, renders the relay of the invention devoid of unwanted mechanical resonances.

Also, the member 36 provides a simple means of holding the pivoted armature 26 in a stationary condition in the envelope 10, whenever the relay is in a state such that the contacts 18 and 28 are open.

20 The relay of the present invention has been found to operate with a high degree of efficiency, even in exceedingly high voltage circuits. It has been found that the magnetic forces provided by the element 16 and armature 26 are sufficient to overcome any counteracting electrostatic forces due to high voltage which are or may be developed in the relay, when the contacts 28 and 18 are open.

25 While a particular embodiment of the invention has been shown and described, modifications may be made. It is intended in the claims to cover all modifications which come within the spirit and scope of the invention.

30 What is claimed is:

1. A vacuum relay including: an evacuated envelope; a first elongated member of magnetizable material positioned in said envelope; a further member of magnetizable material mounted at one end of said envelope coextensive

40 with said first elongated member and extending through said envelope; permanent magnet means mounted externally of said envelope and magnetically coupled through said further member to said first elongated member to establish said first member in a particular magnetic state;

45 a second elongated member positioned in said envelope for selective engagement with said first member and being composed of a material capable of exhibiting first and second distinct states of remanent magnetization; means for pivotally mounting said first elongated member at one end to said further member; an electric coil magnetically coupled to said second member and responsive to electrical pulses of opposite polarities for changing the state of remanent magnetization of said second member where-

50 by the magnetic field thereof selectively aids and opposes the magnetic field of said first member; a member of magnetizable material; and means for supporting said last named magnetizable member in said envelope in position to be engaged by the free end of said first elongated member and magnetized thereby when said first elongated member is out of engagement with said second elongated member; said last named magnetizable member serving to hold said first elongated member against vibratory movement when so engaged thereby.

55 2. The vacuum relay defined in claim 1 in which said permanent magnet is removable.
